ATTORNEY.

UNITED STATES PATENT OFFICE

WALTER F. KLEIN, OF MILWAUKEE, WISCONSIN, ASSIGNOR TO SNAP-ON WRENCH COMPANY, OF MILWAUKEE, WISCONSIN, A CORPORATION OF WISCONSIN

METHOD OF MAKING SOCKET WRENCHES

Application filed August 4, 1928. Serial No. 297,530.

This invention relates to a method of making socket wrenches and more particularly straight walled sockets, although it may be employed with equal advantage for other purposes.

The usual method of forming the nut-engaging portion of a socket wrench or detachable wrench sockets is to bore a hole in the stock to the required length, then under-
10 cut or provide an annular groove at the bottom of the wrench engaging portion and then broach out the hole to form the nut or bolt engaging faces of the socket, the annular groove being cut in so that the chips will
15 break off as they are sheared in communication therewith. This method embodying the use of the annular groove is objectionable because the formation of this groove necessi-
20 tates a special, rather slow and costly opera-
tion of boring and at the same time it either
weakens the wall of the shank of the socket
or necessitates a greater amount of stock to
strengthen this wall. Furthermore, thick-
25 ening the wall prevents the wrench from
being used in places where the clearances are
close. According to the present invention the
step of boring out or otherwise forming the
annular groove is dispensed with and the
30 socket, after being broached to the required
length, has the chips removed at its shank,
preferably simultaneously, in any suitable
manner by a shearing or similar operation
thus preserving the original wall thickness
35 and greatly reducing the cost of producing
the finished article.

The invention further consists in the several features hereinafter set forth and more particularly pointed out by claims at the conclusion hereof.

40 In the drawings:

Figure 1 is a front elevation view of a wrench socket before broaching.

Figure 2 is a detail sectional view taken on the line 2-2 of Figure 1.

45 Figure 3 is a view similar to Figure 2, showing the broaching step.

Figure 4 is a detail sectional view taken on the line 4-4 of Figure 3.

50 Figure 5 is a view similar to Figure 3 showing the chip removal step.

Figure 6 is a perspective view, partly in section, showing the finished socket.

It will be understood that the invention is applicable to those sockets formed integral with their handle, the whole tool being des-
55 ignated a socket wrench, and those sockets which are detachable from interchangeable handles or used with other sockets on the same handle and known as wrench sockets.

The method is illustrated in connection with a wrench socket which initially comprises a partly finished socket prepared for broaching by boring the hole 8 therein or axially therethrough. As previously pointed out, the next usual step in the formation of the socket is to cut an annular groove in the shank portion of the socket which necessitates the use of a cutting tool that must be inserted in the hole 8 for longitudinal and then lateral feeding with a lathe or other equipment designed for that purpose. In accordance with the teachings of the present invention, this step with the disadvantageous structural design thereof, is entirely obviated in that the socket 7 is immediately 75 broached by resort to any suitable broaching tool in accordance with the customary practice.

The broach 9 then proceeds axially in the bore 8 for any selected distance to cut or form the longitudinally disposed, circumferentially spaced grooves in the stock to constitute nut or bolt engaging corners or faces 10. During this operation the chips 11 are forced outwardly and downwardly (see Figure 3), and then the chips are sheared or otherwise broken off by any suitable tool to form the completed socket. I prefer to cut or break off all of the chips 11 simultaneously by resort to a suitable plain broach or shearing tool attached to any appropriate holder 13, it being of a diameter to almost embrace the interior surface of the bore 8 for free axial movement therein to complete its operation. As a result, the chips 11 are segregated from the bore 8 to present a finished socket (Figure 6).

Various changes may be made in the embodiment of the invention herein specifically described without departing from or

sacrificing any of the advantages of the invention as defined in the appended claims.

What I claim as my invention is:

1. The method of forming wrench sockets from stock which consists in forming a socket bore therein, broaching said socket bore to form nut corner engaging means with consequent chip formations extending within said bore, and then separating the chips from the bore of the stock at their region of joinder therewith.
2. The method of forming wrench sockets which consists in forming a bore entirely through stock material, partially broaching said bore to form nut engaging corners with consequent chip formations therein, and then severing the chips from the bore by a shearing operation to effect the removal thereof through the unbroached portion thereof.
3. A method of forming wrench sockets which consists in providing a bore axially through cylindrical stock, partially broaching said bore from one end with consequent chip formations joined to the interior of said stock, and then effecting the severance of said chip formations for discharge from said bore.
4. A method of forming straight exterior walled wrench sockets which consists in providing an axial bore through cylindrical stock, then partially broaching said bore from one end to define nut engaging corners with a surrounding wall of such thinness as to afford nut turning with minimum clearance, and effecting a shearing severance of the joined chip formations for discharge through the other end of said bore.

In testimony whereof, I affix my signature.

WALTER F. KLEIN.
